UNITED STATES PATENT OFFICE.

BURTON E. KINGSLEY, OF SCRANTON, PENNSYLVANIA.

ELEVATOR.

No. 820,208.

Specification of Letters Patent.

Patented May 8, 1906.

Application filed August 15, 1905. Serial No. 274,318.

To all whom it may concern:

Be it known that I, BURTON E. KINGSLEY, a citizen of the United States, residing at Scranton, in the county of Lackawanna and State of Pennsylvania, have invented certain new and useful Improvements in Elevators; and I do hereby declare the following to be a full, clear, and exact description of the invention, such as will enable others skilled in the art to which it appertains to make and use the same.

This invention relates to improvements in elevators, and particularly to a safety mechanism therefor.

The object of the invention is the provision of means for causing the uprights of a car or cage to be forced against the guides between which said car is positioned for partly or entirely stopping the descent thereof.

With this and other objects in view the invention consists of certain other novel constructions, combinations, and arrangements of parts, as will be hereinafter fully described, illustrated in the accompanying drawings, and more particularly pointed out in the claims hereto appended.

In the drawings, Figure 1 is a view in side elevation of a mechanism constructed in accordance with the present invention, said

mechanism being shown in its normal position. Fig. 2 is a view similar to Fig. 1, except the parts of the mechanism are shown in the position assumed when actuated for partly or entirely stopping the descent of the

car or cage. Fig. 3 is a top plan view of the mechanism, taken above the cross-head of the cage and showing the guides in section and a fragmentary view of the floor or platform of the car or cage. Fig. 4 is a fragmentary view of the mechanism taken on line 4-4, Fig. 1. Fig. 5 is a perspective view of the eccentric and the movable toothed roller coacting therewith.

Referring to the drawings by numerals, 1 designates vertical guides, between which the car or cage is positioned. The car or cage comprises in its construction vertical uprights 2 2. Secured to the lower end of said uprights 2 2 are parallel transverse cleats. 50 Secured transversely to the cleats 3 3 are parallel supporting members 4 4, upon which the floor or platform 5 is formed. Each of the uprights 2 is notched at 6 upon each side near its upper end for receiving one of the bifurcated ends 7 of the horizontal cross-

head 8. Stays 9 9 are preferably secured to the ends of the parallel supporting members 4 and are passed over the cross-head 8, bracing the floor or platform 5. By reason of the bifurcated structure of the cross-head 8, Fig. 60 3, the vertical uprights 2 2 are capable of lateral movement, as they are loosely positioned between the bifurcated ends 7 7 of the cross-head 8.

Upon each of the uprights 2 are secured 65 guide members 10, which are provided with parallel outer ends engaging the sides of the uprights 1 1. These guide members are preferably substantially U-shaped. They prevent the car or cage from becoming removed 70 from between the guides. The guide members constitute guiding means which surround a portion of the guides 1 for retaining the car at all times between said guides. The body or that portion of the guide members 10 en- 75 gaging the uprights 2 is preferably countersunk in the outer face of said uprights. These substantially U-shaped guide members are the equivalent of longitudinal grooves upon the guide-engaging sides of the uprights. 80 The guides 1 would be positioned within the longitudinal grooves in the same manner as they are positioned between the parallel sides of the guide members.

I have provided means whereby in the 85 event of an accident happening to a car the uprights 2 2 may be pressed against the inner edge or surface of the guides 1 1 and retard or entirely stop the descent of the car or cage. Of course the uprights 2 2 are connected to 90 the transverse cleats 3 for supporting the platform 5; but this connection will not prevent of the slight lateral movement of the uprights 2, which causes the same to bind or press against the inner edges of the guides, Fig. 2. 95 The means for causing the lateral movement of the uprights 2 for jamming or pressing the same against the uprights 1 for retarding the movement of the car or cage comprises primary and auxiliary horizontal shafts 12 and 100 13, respectively. The shaft 13 is provided with a primary arm 14 and an auxiliary arm 15. These arms are secured at substantially right angles to each other. The primary arm 14 is connected at its outer end to a vertical bolt 16. The bolt 16 is provided with a headed upper end 17, to which the hoisting-cable 11 is preferably connected. The bolt 16 passes through an apertured portion of the cross-head 8. The lower end of the bolt 110

is threaded at 18, and upon the threaded portion a nut 19 is positioned. Above the nut 19 and secured upon the bolt 16 is a flat spring 20. The spring 20 is secured at its 5 ends to the uprights 2 2 and is adapted to exert a downward pressure upon the nut 19 for assisting in moving the primary arm 14 downward when the hoisting-cable 11 is severed or broken. Loosely mounted upon the primary revoluble shaft 12 is an eccentric 21, Fig. 5. Integral with the eccentric 21 is a lever-arm 22, which is provided with apertures 23. Fixedly secured to the outer end of the primary shaft 12 and contiguous to 10 the eccentric 21 is a roller 24, which is provided with a roughened surface 25, constituting a toothed wheel. The eccentric 21 is positioned within a bracket 26, removably secured by any suitable means to one of the 15 uprights 2. Secured upon the other upright 2 is a bracket 27, similarly constructed to bracket 26, but of less dimensions. One end of the primary shaft is journaled in the bracket 27, while its opposite end portion is 20 journaled in the eccentric 21, the extreme end being fixedly secured within the toothed roller 24. A flexible member 28—as, for instance, a helical spring—is secured at one end in one of the apertures 23, and its opposite end is secured at 29 to an upright 2. The auxiliary arm 15 is connected to the lever 22, preferably by a chain 30, Fig. 4. The end of the chain or connecting means 30 is secured in the apertured portions of the lever 22 and 25 the arm 15. The auxiliary shaft 13 is journaled in brackets 31, which are secured upon the uprights 2 2 opposite to the brackets 26 and 27. A pair of parallel plates 32 is secured upon each of the uprights 2 below the 30 horizontal revoluble shafts 12 and 13. Between these plates 32 are pivotally secured sets of pivotally-connected members 33 and 34, which constitute a toggle-bar. A pulley or grooved wheel 35 is connected to the inner 35 ends of the lower members 33 33 by any suitable means. A flexible member 36—as, for instance, a chain—is secured to the inner ends of the members 34 34 in any suitable manner, and its opposite end is fixedly secured centrally to the shaft 12. When 40 rotary movement is imparted to the shaft 12, the chain will be wound around the same and will cause the toggle-bar to be drawn together, and consequently spread the uprights 2 apart, Fig. 2. Rotation of the shaft 12 is caused by means of the toothed roller 24 and one side of a guide 1.

When the hoist-cable 11 is severed, the flat spring 20 will assist in throwing arms 14 and 45 15 forward, consequently permitting of the spring 28 to pull the lever 22 of the eccentric 21 downward, and thereby placing the shaft 12 near to the upright which is contiguous to the toothed roller 24. The toothed roller 60 65 will be placed in engagement with the up-

right 1, and as the car descends shaft 12 will be rotated and the chain wound around the same, as clearly seen in Fig. 2. The winding of the chain will of course through the medium of the pulley compress the members of 70 the toggle-bar, and consequently jam the uprights against the guides, for the reason that said toggle-bar acts as a cam or wedge for forcing said uprights to engage the inner edges of the guides. If the descent of the 75 car or cage is not entirely stopped, it will be retarded to such an extent as to prevent of any injury thereto or to its occupants.

Ordinarily the car is lifted through the medium of the hoisting-cable 11 and the bolt 16. 80 It will be seen in Fig. 1 that when the car is in position to be freely moved between the guides 1 1 the spring 20 will be bowed to a greater extent than when the uprights are jammed against the guides 1, Fig. 2. When 85 the bolt 16 is in the position depicted in Fig. 1, the arm 14 will be lifted, thereby placing the arm 15 at an angle to a vertical plane, Fig. 4, and through the medium of the connecting means 30 the eccentric will be so positioned as to place the primary shaft 12 in its farthest position away from one of the uprights 2, and consequently placing the toothed wheel away from the guide 1. The releasing 90 of the rotatable shaft 12 by disengaging roller 24 from a guide 1 permits the members of the toggle-bar to move apart, particularly when the flat spring 20 is lifted, as shown in Fig. 1, as the lifting of the central portion of said spring will cause its ends to be 95 drawn inward slightly, sufficiently to permit the uprights 2 2 to be removed from in engagement with the guides 1, Fig. 1.

What I claim is—

1. In a mechanism of the class described, 105 the combination with parallel guides, of a car provided with movable uprights positioned between said guides, a toggle-bar secured to said uprights, a rotatable shaft carried by said uprights, flexible means connecting diametrically opposite parts of said toggle-bar and fixedly secured to said shaft, and means for rotating said shaft and thereby winding said flexible means thereon, for compressing 110 said toggle-bar.

2. In a mechanism of the class described, 115 the combination with guides, of a car provided with laterally-movable uprights positioned between said guides, a toggle-bar positioned between and connected to said uprights, a rotatable shaft carried by said uprights, flexible means connecting diametrically opposite parts of said toggle-bar and fixedly secured to said shaft, a roller fixedly secured to said shaft, and means for moving 120 said roller to an engaging position with a guide, whereby movement of the car will cause rotation of said roller and shaft and compression of said toggle-bar, through the medium of said flexible means.

3. In a mechanism of the class described, the combination with vertical guides, of a car provided with a cross-head positioned between said guides, said cross-head provided with bifurcated ends, laterally-movable uprights carried by said car and positioned within the bifurcated ends of said cross-head, a toggle-bar connected to said uprights, primary and auxiliary, revoluble shafts positioned upon opposite sides of said uprights, said auxiliary shaft provided with primary and auxiliary arms positioned at substantially right angles to each other, a bracket formed upon one of said uprights, an eccentric provided with a lever, loosely mounted upon said primary shaft, within said bracket, a toothed roller fixedly secured to one end of said primary shaft and contiguous to said eccentric, a spring secured at one end to said lever and at its opposite end to an upright, means connecting said lever and auxiliary arm, flexible means connected to diametrically opposite parts of said toggle-bar and fixedly secured to said primary shaft, a vertically-movable member positioned within said cross-head and secured to said auxiliary arm, and a spring secured at its end to said uprights and in engagement with said vertically-movable member.
4. In a mechanism of the class described, the combination with vertical guides, of a car positioned between said guides, of substantially parallel, movable members carried by said car, a toggle-bar secured to said movable members, a shaft provided with an eccentric carried by said car, a flexible member connected to diametrically opposite parts of said toggle-bar and fixedly secured to said shaft, a toothed member fixedly secured to said shaft and adapted to engage one of said guides, and means for moving said eccentric for adjusting said toothed member.
5. In a mechanism of the class described, the combination with guides, of a car provided with parallel, laterally-movable means, a toggle-bar connected to said laterally-movable means, a shaft provided with an eccentric carried by said car, a pulley secured upon one side of said toggle-bar, a flexible member secured to one side of said toggle-bar and passed around said pulley and fixedly secured to said shaft, a toothed member fixedly secured to one end of said shaft, and means for moving said eccentric, and thereby adjusting the toothed member.
6. In a mechanism of the class described, the combination with guides, of a car provided with movable guide-engaging means, a toggle-bar carried by said car, a shaft provided with toothed means carried by said car, a flexible member connected to said toggle-bar and shaft, and means for adjusting the shaft for placing the toothed portion in different positions for controlling movement of said flexible member and toggle-bar.
7. The combination with vertical guides, of a car provided with movable uprights, positioned between said guides, a toggle-bar mounted upon said uprights, rotatable means carried by said car, and flexible means connected to said toggle-bar and rotatable means and capable of being wound upon said rotatable means for compressing said toggle-bar and thereby causing said uprights to clamp upon the guides.
8. The combination with guides, of a car provided with laterally-movable uprights positioned between said guides, a toggle-bar engaging said uprights, means engaging diametrically opposite parts of said toggle-bar and being capable of compressing said toggle-bar for causing said uprights to clamp the guides.
9. The combination with guides, of a car provided with laterally-movable uprights, constituting sides, positioned between said guides, a toggle-bar engaging said uprights, a rotatable member carried by said car, and flexible means connecting said toggle-bar and rotatable member and capable of compressing said toggle-bar when movement is imparted to said rotatable member.
10. The combination with vertical guides, of a car provided with laterally-movable uprights, positioned between said guides, a toggle-bar carried entirely by said uprights, said toggle-bar comprising sets of members, and means for closing said sets together for causing said uprights to clamp the guides.
11. The combination with guides, of a car provided with laterally-movable uprights, positioned between said guides, a toggle-bar pivotally mounted at each end upon said uprights, said toggle-bar comprising sets of members, and means engaging diametrically opposite portions of said toggle-bar and capable of drawing the sets of members of said toggle-bar together for moving said uprights outward.
12. The combination with guides, of a car provided with movable uprights, constituting the sides of said car, positioned between said guides, a revoluble shaft carried by said car, means connected to said shaft and being capable of separating said uprights, when rotary movement is imparted to said shaft.
13. The combination with guides, of a car provided with movable uprights, positioned between said guides, a toggle-bar pivotally secured at each end to said uprights, said toggle-bar comprising sets of members, and means for simultaneously drawing the sets of members of said toggle-bar together for moving the uprights into engagement with said guides.
14. The combination with guides, a car provided with laterally-movable members positioned between said guides, a toggle-bar positioned between said uprights, said toggle-bar comprising sets of members, and

means for compressing said sets of members for moving said laterally-movable members against said guides.

15. The combination with guides, of a car provided with movable guide-engaging means, a toggle-bar carried by said car, a shaft provided with toothed means carried by said car, means connecting said toggle-bar and shaft, and a capable of compressing said toggle-bar 10 when rotary movement is imparted to said toothed means and shaft.

16. The combination with guides, a car positioned between said guides, of guide-engag-

ing members carried by said car, a toggle-bar engaging said guide-engaging members, said toggle-bar comprising sets of members, and means connected to and being capable of drawing said sets of members together for moving said guide-engaging members.

In testimony whereof I affix my signature 20 in presence of two witnesses.

BURTON E. KINGSLEY.
